US00D517157S

(12) **United States Design Patent** (10) Patent No.: **US D517,157 S**
Rae (45) Date of Patent: **** Mar. 14, 2006**

(54) **KNIFE**

(75) Inventor: **Kit Rae**, Kodak, TN (US)

(73) Assignee: **United Cutlery Corporation**,
Sevierville, TN (US)

(**) Term: **14 Years**

(21) Appl. No.: **29/215,897**

(22) Filed: **Oct. 26, 2004**

(51) LOC (8) Cl. **22-02**

(52) U.S. Cl. **D22/118**

(58) Field of Classification Search D22/118,
D22/117-120; D8/95-99; D21/568; 30/294,
30/295, 151-154, 160

(57) **CLAIM**

I claim the ornamental design for a knife, as shown and
described.

DESCRIPTION

FIG. 1 is a perspective view of the design of the present
invention for a knife;

FIG. 2 is a perspective view of knife of FIG. 1 wherein the
knife blade is received within the handle of a second knife
of FIG. 1, the features of the second knife being shown in
broken lines for illustrative purposes only and forming no
part of the claimed design;

FIG. 3 is a front elevation view of the knife of FIG. 1;

FIG. 4 is a rear elevation view of the knife of FIG. 1;

FIG. 5 is a left side elevation view of the knife of FIG. 1, the
right side elevation being a mirror image thereof;

FIG. 6 is a top end view of the knife of FIG. 1; and,

FIG. 7 is a bottom end view of the knife of FIG. 1.

1 Claim, 5 Drawing Sheets
